PROCESS OF APPLYING INDICIA TO CELLOPHANE AND THE LIKE

Application filed November 11, 1930. Serial No. 494,839.

The invention relates to the process of producing impressions in the form of labels, bands or other indicia, embodying a metallized medium and usually one or more colors on a web or individual strips of cellophane or other material, such as cellulose acetate paper, glassine paper, etc.

The invention is particularly adapted to cellophane in web form or individual predetermined lengths, for enclosing cigars, in which instance of use the impression applied to the cellophane pursuant to my process may simulate a so-called cigar band, such indicia when applied to the web being spaced in proper relation to one another and in proper relation to the edges of the cellophane strip, whereby severed individual lengths are adaptable to be fed to present day machines for enclosing individual cigars in so-called pockets of the cellophane material. However, my invention is not limited to such specific applications and may be utilized for applying indicia of any desired character embodying a metallized medium.

Pursuant to my invention, the web of cellophane or other enclosing material is impressed with indicia at definite spacing from one another and with respect to the edges of the web, the indicia embodying an impression including a metallized medium and usually one or more colors. The desired color or colors are preferably applied by individual printing rolls corresponding to the number of the desired colors, which color impressions may be effected either before or after, or both before and after the step of applying the metallized medium.

The metallized medium is preferably applied by the use of a rotary roll, suitably driven, adapted to carry a die or set of dies, under proper temperature control, to which dies are applied in sequence a regulated film of waxy or equivalent material, on which is imposed a regulated layer of the metallizing medium or media, whereby the desired indicia are impressed upon the web at the desired spacings relative to one another and relative to the edges of the web. If desired, the indicia may be wholly or in part embossed, the

embossing operation being carried out preferably subsequent to the metallizing step.

Further features and objects of the invention will be more fully understood from the following detail description and the accompanying drawings, in which

Fig. 1 is a plan view of a fragment of a strip bearing an indicia in the form of a band applicable for enclosing cigars. The indicated dimensions of the strip and the relative location of the band are applicable to a strip length for forming a so-called pocket for individual cigars.

Fig. 2 is a plan view of an individual pocket with a cigar enclosed therein in proper relation to the indicated band.

Fig. 3 is a sectional elevation through the material at the location of the applied band, showing the respectively imposed materials, the relative thicknesses of the parts being exaggerated for the sake of clarity.

Fig. 4 is a sectional elevation similar to Fig. 3 showing a modification.

Fig. 5 is a diagrammatic view in central elevation, partly in central vertical section, illustrating certain essential steps of my invention.

Fig. 6 is a side elevation, in diagrammatic form, illustrating my invention for the application of indicia such as band labels for cigars or the like, embodying one or more colors in addition to metallized impressions, applied to an indefinite strip length or the like at predetermined spacing.

Fig. 7 is a top plan view of a portion of the mechanism for applying metallized impressions.

Referring to Figs. 1 and 2, the cellophane or other material is indicated at 10, the indicated dimensions of the sheet corresponding to that of a severed length cut from a web. The indicia 11 in this instance is in similitude of a cigar band by reason of the article to be enclosed being a cigar, the impression band being disposed at proper spacing from the opposite edges 12, 13 and 14, 15, the edge 12 being proximate the butt end of the cigar, the edge 13 being proximate the point of the cigar, the edges 14, 15 being folded in overlapping relation to one another at the back

of the cigar, it being understood that the ends of the resulting pocket are folded upon one another to provide for full or substantially full sealing of the pocket, with or without 5 the use of sealing or other adhesive.

In the particular indicia 11, shown in the form as simulating a band, the metallic medium, which may be genuine or imitation gold, genuine silver or its imitation, or other 10 desired metallic medium as indicated at 16. This particular indicia may also include two colors, say red and black, as at 17 and 18.

The colors such as 17 and 18, of any desired 15 number and desired locations, are applied to 15 the material either before or after the application of the metallic medium or media.

Fig. 3 shows in diagrammatic cross-section, the cellophane at 10, the undermost layer of sizing, such as shellac at 18, the superposed 20 metallic medium, such as bronze, at 19, and the outermost layer, such as wax or other suitable unctuous material, at 20. In such instance the layer 18 serves as the initial bonding medium, the bronze or other metallic medium being superposed upon the same. 25

As appears more fully hereinafter, the indicia bears suitable trade or other name or names effected by means of suitable dies or sets of dies, the dies being heated to proper 30 elevated temperature afforded by means of an electrical resistance unit or other suitable controlled heating means.

Fig. 4 corresponds to Fig. 3, except that the initial bonding layer 18 is omitted, the bonding 35 of the metallic medium 19 and superposed wax medium 20 being effected directly upon the material. Like parts are indicated by like reference numbers.

I have illustrated in Fig. 5 in diagrammatic form, one manner of applying the metallic medium or media to a web of cellophane 40 or other enclosing material.

At 21 is indicated a supply roll, the web 22 of which is passed through the indicated 45 guiding and operating parts and rewound if desired in the form of a roll as indicated at 23. The dies 24, or set of such dies, are mounted on a suitable printing roll 25, the shaft 26 of which is suitably driven in the 50 direction of the indicated arrow 27. At 28 is represented a bath 29 of suitable waxy or other unctuous composition, kept fluid by suitable heating means (not shown), the roll 30 serving to supply the waxy material from 55 the bath 29 to the face of a die 24 when in engagement with the supply roll 30. At 31 I indicate a wiping roll and at 32 a "doctor" in the form of a wiping plate, whereby to regulate the film upon the effective surface of 60 the supply roll 30, rotated in the direction of the indicated arrow 33.

It will be understood that the individual dies 24 or the printing roll 25 itself may be suitably heated to the proper temperature, as 65 by means of electrical resistance, referred to

hereinafter, whereby the film of the unctuous material supplied to the face of each die during the stage of engagement by the supply roll 30 is maintained in proper condition for the completion of the operation.

At 34 is diagrammatically indicated a suitable bronzing machine or equivalent for supplying bronze or other desired metallic medium applied to the die as a layer superimposed upon the waxy composition. In this instance I have indicated at 35 the use of a single metallizing medium, such as bronze, contained in the hopper 36, at the discharge end of which is disposed a supply brush 37 suitably rotated in the direction of the indicated arrow 38. At 39 is represented suitable means for removing any excess of metallic medium and diagrammatically illustrated as comprising the wiping brush 40 disposed at the inlet opening of the conduit 41 provided with the indicated exhaust fan 42, the recovered metallic medium being collected through the discharge outlet 43.

The pairs of rolls 44, 44, and 45, 45, serve as guide rolls, one or both of which may be directly driven to serve as feeding rolls, the pair of rolls 45, 45, being preferably arranged to act as pull rolls.

Coacting with the printing roll 25 is arranged an impression roll 46, driven in the direction of the applied arrow, having a surface of leather, paper, or other suitable resilient material, thereby to derive impressions corresponding to the outlines of the dies 24.

At 47 I have indicated a wiping roll rotated in the direction of the indicated arrow to clean the dies 24 after each impression operation, the removed material being recovered through the exhaust conduit 47.

Accordingly, upon contact of the one or more dies 24 carried by the printing roll 25 with the face of the web 22, the metallized medium is deposited and bonded to the web face in correspondence to the outlines of the configuration of the die faces, that is to say, with the lettering, wording, symbols, inner and outer outlines, etc., of the respective dies portions, as may be desired.

Where an initial bonding medium is desired or required, such bonding medium may be applied by the use of a roll 50 driven in the direction of the indicated arrow, and provided with a protuberance 51 corresponding at its effective face to each die 24, the desired initial bonding medium, such as shellac or other sizing, etc., being provided by means of a receptacle 52 and a supply roll 53, driven in the direction of the indicated arrow, whereby such sizing or other initial bonding material is applied upon the face of the web in advance of and in proper register with the subsequently applied metallic impression. The roll 54 coacts with the protuberance 51 of the roll 50 in the nature of an impression roll.

I have also indicated at 78 suitable means for applying the sizing or other adhesive, in lieu of the roll 50, the sizing in this instance being applied upon the metallic medium on each die. The film of the adhesive thus applied is supplied by the roll 79, driven in the indicated direction and provided with a film regulating roll and "doctor", similarly as in the application of the waxy film.

10 If desired, the unit 51 may apply a medium serving to soften or otherwise prepare the surface of the web for the reception of the impressed material and unit 78 may supply a protective medium such as cellulose acetate.

15 In many instances it is desirable to emboss the applied metallic impression, which may be effected by the use of the embossing roll 55 indicated as disposed subsequent to the printing roll 25; the roll 55 is provided with an embossing protuberance 56 and is driven in the direction of the indicated arrow 57. The roll 55 has a cooperating impression roll 58, effective spacing of the embossing protuberance 56 being regulated to register with the whole or a part of the metallic or other impression desired to be embossed.

In Fig. 6 there is diagrammatically shown a preferred sequence of operation of applying a plurality of colors as well as metallic medium to the web. The metallizing unit is indicated at 60, the constituent parts conforming generally to that illustrated in Fig. 5 and correspondingly identified by reference numbers. The supply reel is indicated at 61 and after passing through the indicated sets of guides and feed rolls, the web 62 is passed through the first color printing unit 63, thence to a second color printing unit 64, thence past the metal impression unit, thence 40 a third color unit 65, fourth color unit 66, etc., the colors being as desired in number, location or locations, etc., it being understood that the printing surfaces of the respective color printing units corresponding to one another and with respect to the outline of the die of the metallizing unit 60, appropriately to the desired outlines of the constituent parts forming the total indicia, it being further understood that a unit for applying the 45 initial bonding material is employed in advance of the metallizing unit and also a unit for embossing, similarly as is set forth in the embodiment of my process as illustrated in Fig. 5.

50 My process is applicable also to effect impressions in multiple across the web, for the metal impression unit, as well as for the respective printing, initial bonding unit and the embossing unit.

55 Fig. 7 illustrates multiple dies 67 arranged in alignment with one another on the periphery of the printing roll 25, and similarly as in the arrangement of Fig. 5, the dies may be distributed about the peripheral 60 surface of the printing roll 25.

Fig. 7 also illustrates the use of electrically heated resistances for the respective dies, the indicated electrical conductors, the brushes 70, 71, commutators 72, 73, to the bars of which are connected the individual leads 74 of the electrical heating units.

Suitable means are provided for the synchronous drive of the respective printing, metallizing, bonding and embossing units, etc., as will be understood by those skilled in the art.

It is preferable to sever the web of cellophane or other enclosing material longitudinally of its length, which may be carried out by the provision of sets of rotating knives 75, 75, see Fig. 6, and individual re-wind devices 76 for the respective longitudinally severed strips, which re-wind devices 76 preferably wind the longitudinal strips 77 with the axis in vertical position, as indicated in Fig. 6.

The individual longitudinal strips of cellophane or other enclosing material bearing the indicia at longitudinal spacing therein are now applicable for use in wrapping machines of present day construction, employing cellophane, cellulose acetate paper, etc.; usually the web is severed along desired predetermined transverse lines to form the individual lengths for the individual "pockets" for cigars, suitable treatment of the web or longitudinal severed strips thereof being carried out for other articles as may be desired, the location of the indicia on each individual strip conforming to proper position of the same when the enclosing material has been 100 enwrapped about the article.

The strips of enclosing material may also be provided with opaque "spots", openings, and the like, applicable for use with so-called electric "eye" devices, as is set forth more 105 fully in the copending application of Arthur M. Wickwire, Serial No. 471,931, filed July 31, 1930.

My invention is applicable for impressing labels and wraps in web and individual 110 lengths, in a similar manner.

Whereas, I have described my invention by reference to specific formations thereof, it will be understood that many changes and modifications may be made without departing 115 from the spirit of the invention.

I claim.

1. The process of impressing cellophane and like enclosing material with indicia embodying metallized medium in an outline corresponding to the die, which comprises imparting substantially continuous motion to the material and the die, applying unctuous material to the die while in motion, then applying metallized medium upon the layer of unctuous material on the die while in motion, and then applying the die thus prepared in impressing contact with the material.

2. The process of impressing cellophane and like enclosing material with indicia em-

bodying metallized medium in an outline corresponding to the die, which comprises imparting substantially continuous motion to the material and the die, applying heated unctuous material to the die while in motion, then applying metallized medium upon the layer of heated unctuous material on the die while in motion, and then applying the die thus prepared in impressing contact under elevated temperature conditions with the material.

3. The process of impressing cellophane and like enclosing material with embossed indicia embodying metallized medium in an outline corresponding to the die, which comprises imparting substantially continuous motion to the material and the die, applying unctuous material to the die while in motion, then applying metallized medium upon the layer of unctuous material on the die while in motion, and then applying the die thus prepared in impressing contact with the material, and then embossing the applied impression.

25 4. The process of impressing cellophane and like enclosing material with indicia embodying metallized medium in an outline corresponding to the die, which comprises imparting substantially continuous motion to the material and the die, applying suitable bonding medium upon the material and applying unctuous material to the die while in motion, then applying metallized medium upon the layer of unctuous material on the die while in motion, and then applying the die thus prepared in impressing contact with the material.

50 5. The process of impressing cellophane and like enclosing material with indicia embodying metallized medium in an outline corresponding to the die, which comprises imparting substantially continuous motion to the material and the die, applying unctuous material to the die while in motion, then applying metallized medium upon the layer of unctuous material on the die while in motion, and then applying the die thus prepared in impressing contact at predetermined spacings longitudinally of a web of the material.

55 6. The process of impressing cellophane and like enclosing material with indicia embodying metallized medium in an outline corresponding to the die, which comprises imparting substantially continuous motion to the material and the die, applying heated unctuous material to the die while in motion, then applying metallized medium upon the layer of heated unctuous material on the die while in motion and then applying the die thus prepared in impressing contact at predetermined spacings longitudinally of a web of the material.

60 7. The process of impressing cellophane and like enclosing material with indicia embodying metallized medium in an outline

corresponding to the die, which comprises imparting substantially continuous motion to the material and the die, applying unctuous material to the die while in motion, then applying metallized medium upon the layer of unctuous material on the die while in motion, and then applying the die thus prepared in impressing contact at predetermined spacings longitudinally and transversely of a web of the material.

75 8. The process of impressing cellophane and like enclosing material with indicia embodying metallized medium in an outline corresponding to the die, which comprises imparting substantially continuous motion to the material and the die, applying heated unctuous material to the die while in motion, then applying metallized medium upon the layer of heated unctuous material on the die while in motion, and then applying the die thus prepared in impressing contact at predetermined spacings longitudinally and transversely of a web of the material.

80 9. The process of impressing material with indicia embodying impressing medium in an outline corresponding to the die, which comprises imparting substantially continuous motion to the material and the die, applying unctuous material to the die while in motion, then applying impressing medium upon the layer of unctuous material on the die while in motion, and then applying the die thus prepared in impressing contact with the material.

90 10. The process of impressing material with indicia embodying impressing medium in an outline corresponding to the die, which comprises imparting substantially continuous motion to the material and the die, applying heated unctuous material to the die while in motion, then applying impressing medium upon the layer of heated unctuous material on the die while in motion, and then applying the die thus prepared in impressing contact under elevated temperature conditions with the material.

105 In testimony whereof I have signed this specification this 7th day of November, 1930.

110 WILLIAM F. GRUPE.
